SCREEN PRINTING MACHINE FOR TEXTILES

Jan Ivo Marek, Margate, and Laurence Steinberg,
Ramsgate, EnglandApplication October 5, 1948, Serial No. 52,952
In Great Britain October 31, 1947

11 Claims. (Cl. 101—126)

1

This invention relates to a screen printing machine for textiles and has for its object to provide such a machine which is completely automatic in operation instead of hand operated as hitherto. A further object of the invention is to provide a machine which is adaptable to a large variety of fabrics.

According to the present invention there is provided a screen printing machine which comprises an endless belt or the equivalent carrier for the fabric to be printed upon, one or more printing appliances including squeegees supported above the belt, means for raising one or all of said appliances at the end of a printing operation and for lowering said appliances prior to the next printing operation, and means for engaging and moving said belt at the end of a printing operation to move the fabric carried by the belt into a position ready for the next printing operation.

According to one form of the invention the machine comprises an endless belt or the equivalent carrier for the fabric to be printed upon, means for moving said belt intermittently to displace the fabric on the belt from below one printing position to below the next printing position in sequence, and a number of printing appliances above said belt which are lowered onto the belt when the latter is stationary to effect printing and which are subsequently raised at the end of a printing operation to enable the belt to be moved forward to position the fabric ready for subsequent printing operations.

To enable the invention to be clearly understood and readily carried into effect, reference will now be made to the accompanying drawings which illustrate one specific form of the invention by way of example.

In the drawings:

Figure 1 is a diagrammatic view of the complete machine.

Figure 2 is a plan view of Figure 1.

Figure 3 is a perspective view drawn to a larger scale showing the mechanism appropriate to one printing position.

Figure 4 is a fragmentary view drawn to a larger scale illustrating the drive for the belt moving mechanism and the squeegees.

Figure 5 is a plan view of the driving mechanism looking in the direction of the arrows V—V of Figure 4.

Figure 6 is in effect a continuation of Figure 4 showing the squeegee actuating mechanism.

Figures 7 and 8 comprise respectively a diagrammatic side elevation and a part plan view showing the mechanism for intermittently elevating and lowering the racks and the subframes for the squeegees.

Figure 9 is a transverse section showing how a rack is supported at each side of the machine, and

Figures 10 and 11 are detail side views of

2

Figure 9 showing a rack and a subframe in lowered and raised positions respectively.

Referring to the drawings, the machine comprises a main frame indicated generally at 1 which carries at its ends rollers 2 and 3 for supporting an endless belt 4 which is driven intermittently as will hereinafter be explained to move the fabric 5 to be printed upon successively to printing positions designated at "A," "B" and "C." With the embodiment being described three printing positions are shown but it will be appreciated that more or less printing positions may be provided according to the number of colours the machine is required to print.

The belt 4 may be made of metal, fabric, rubber, synthetic rubber or any other suitable material and its width is made appropriate to that of the fabric to be printed.

The fabric 5 is fed from a supply reel 6 or the equivalent and the belt 4, prior to picking up the fabric, has a film of adhesive applied to it by means of gumming mechanism 7, the gum by the time the fabric is fed onto it being tacky so that the fabric 5 is adequately secured to the belt to hold it immovable relatively to the latter during printing. After the fabric 5 has been printed upon by all colours it leaves the exit end of the machine at 5a, the printed fabric being stripped from the belt 4 by stripping mechanism not shown.

In the operation the belt 4 is made to move intermittently and printing is effected firstly at stage "A" while the belt is stationary. The belt then moves and again stops with the part of the fabric previously printed at "A" now in the printing position "B" where a second colour is printed, a fresh portion of the fabric having been introduced to the printing position "A." The belt again moves to bring the portion of the fabric printed now in two colours at positions "A" and "B" below the printing position "C" where a third colour is printed, the portion printed at "A" having moved on to position "B" and a fresh portion of fabric moved into position "A."

The printing is effected at stages "A," "B" and "C" by means of squeegees 8, each squeegee 8 as shown in Figure 3 operating in a subframe 9 which is caused to rise when the belt 4 moves and then to move down onto the belt 4 when the latter is stationary, each subframe accommodating a pattern 10 registered in a screen. The squeegees 8 may be of rubber or any other suitable material and each is mechanically operated so as to impress the colour through the pattern 10 onto the fabric 5 resting on the belt 4. After a printing operation has been effected the squeegees 8 cease to move and the subframes 9 are caused to rise leaving the belt 4 free to move on a distance related to the length of the pattern 10.

60 The bar of the squeegee 8 is superposed by a

roller wheel 8b. Thus as the squeegee is moving to the one, or other side of the subframe, it is lifted to an appropriate height owing to angles on the side of the subframes. As the bar is sliding over the angles, the roller wheel 8b is moving in the same direction on a rail. This rail is interrupted on both sides of the frame and by this the squeegee is automatically reversed on both sides of the frame by an angle of approximately 90° before falling (in returning back over the 10 angle pieces of the frame) down on the printing pattern.

With certain dyes and with some materials it is possible to use solvents of high volatility to facilitate drying of the colour while the fabric 5 is moving on the belt 4 from stage "A" to stage "B" or from "B" to "C." In cases however where the drying of the colour needs to be accelerated, one or more electrically heated rollers 11 may be provided for engaging with the moistened surface of the fabric 5. Alternatively, the distance between the printing stages may be such that one or more repeats of the printing effected at stage "A" takes place before a colour printed at "A" reaches stage "B" thereby increasing the time available for drying to take place. Other drying devices may be employed such as infra-red radiation, steam, hot and cold air or other suitable means indicated generally at 12.

The means for driving the printing mechanism 30 and the belt 4 comprises, see particularly Figures 4 and 5, an electric motor 13 or any alternative form of power which drives a shaft 14 by way of a belt 15 and reduction gearing or torque converters 16, the shaft 14 serving to drive all the 35 operating mechanisms although individual motors or the equivalent may be employed for this purpose.

The intermittent driving of the belt 4 is effected through a vertical shaft 17 which is driven by 40 the shaft 14 by way of bevel gearing 18. This shaft 17 is fitted at its upper end with a crank arm 19 provided at one end with an upstanding pin 20 which engages and slides within a channel section member 21 which bridges a pair of bars 45 or racks 22 provided one at each side of the machine. The arrangement being such that as the pin 20 traverses a circular path the member 21 and accordingly the bars 22 are caused to move backwards and forwards of the machine a distance related to the length of the pattern 10.

The bar 22 at each side of the machine is slidably supported in a channel section member 23 which is adapted to be intermittently raised and lowered to cause teeth or projections 24 on the upper edges of the bars 22 to engage in openings 25 formed at intervals along each longitudinal edge of the belt 4. The openings 25 in the belt 4 may be reinforced if desired depending upon the nature of the material of the belt.

The means for raising the channel section member 23 at each side of the machine comprises a rockable lever 26 at each side of the machine which is pivoted at its lower end 27 to a part of the machine frame 1 and has a pin and slot connection at its upper end with the appropriate member 23. Each lever 26 is fitted between its ends with a pin, roller or other anti-friction means 28 which is engaged by the edge of a cam 29 provided one at each end of the shaft 14. Each cam 29 is formed with a rise 30 which extends around half the periphery of the cam and the levers 26 are rocked about their pivots 27 when the rises 30 engage the pins or rollers 28 and move the members 23 endways slightly 75

and cause inclined projections 31 on each member 23 to ride upwardly over rollers 32 supported by arms 33 rigidly connected to a longitudinal frame member 1 at each side of the machine. Correspondingly, the bar or rack 22 in each member 23 is caused to rise and the teeth or projections 24 are engaged in the openings 25 in the belt 4 so as to move the latter between printing operations as the racks are moved by the members 21.

The mechanism for elevating the bars or racks 22 is also utilised to elevate the subframes 9 for the squeegees 8 at the various printing stages and this is effected by subsidiary inclined projections 34 on the upper edge of the member 23 which are moved underneath rollers 35 carried at the lower ends of bars 36 secured to the subframes 9 so that simultaneously with the raising of the racks 22 to engage the teeth 24 in the openings 25 the subframes are also raised free of the belt 4. The racks 22 are interconnected by transverse and diagonal bracing members 22a to ensure uniform movement.

The squeegees 8 of the three subframes 9 are moved by a common reciprocating rod 37 which is connected to each of the squeegees 8 and at one end to a link 38 which is pivoted at its lower end 38a to the frame 1 of the machine and intermediate of its ends to a connecting arm 39 actuated by a crank 40 mounted on one end of a shaft 41 fitted with a gear 42 which is driven by a gear 43 having teeth provided half way around its edge only, this latter gear being mounted on a shaft 44 carrying a gearwheel 45 driven by a chain 46 from a gear 47 on the shaft 14.

The sequence of operation of the parts is such that when printing is being effected at the various stages "A," "B," and "C" the belt 4 is stationary, the subframes 9 down on the belt; the half gear 43 operating to move the squeegees 8 forwards and back again to their original positions and the racks 22 which are clear of the belt moving back to their initial positions ready for a subsequent operation.

At the end of a printing operation the racks 22 are moved into engagement with the belt 4; the subframes 9 raised clear of the belt and the belt moved forwards to carry the fabric 5 from the printing stage just effected onto the next successive printing stage or, from the last printing stage of the machine onto the apparatus which strips the fabric 5 from the belt 4 where it leaves the exit end of the machine. During this time the nonoperative part of the half-gear 43 registers with the gear 42 so that the latter is not driven and the squeegees 8 remain stationary.

The foregoing embodiment has been described merely by way of example and it will be appreciated that modifications are possible to the mechanisms described within the scope of the invention. For example, instead of employing racks to move the belt 4 intermittently, the belt may have friction material applied to one or both of its surfaces and the belt moved by clamps which grip the belt and move it in one direction and afterwards release the belt and move back again ready to seize the belt again and move it on when the next printing operation has ceased. Alternatively, the belt 4 may be moved by means of teeth formed on a drum which engage through the holes in the belt or photo-electric or other optical or solenoid devices may be used to ensure the engagement and disengagement of the

belt drive at times appropriate to the positions of the screens in the subframes.

The means for simultaneously lifting and lowering the subframes 9 for the screens may also be varied and other mechanical or pneumatic, hydraulic or electrical jacking or lifting apparatus or other suitable means used.

Also the half-gear mechanism 43 for moving the squeegees 8 backwards and forwards may be replaced by any other interrupted drive mechanism common in engineering practice. For instance, the squeegees 8 may be chain driven and the subframes 9 provided with sprocket wheels on each side and which are so driven that those on one side rotate in the opposite direction to those on the other side, the wheels on each side working alternately.

Each of the squeegees 8 may consist of one or more strips of rubber or other suitable material having a relatively soft surface and which are flexible, the strips being connected along one edge in a channel 8a or other suitable holder which is permanently or detachably fixed to a bar connected to the link 31. Conveniently, each squeegee 8 may slide at its ends on the side of its subframe which act as guides and also restrict lateral movement of the squeegee.

The means for supplying the colour to the various squeegees 8 may consist of a gravity feed or other simple means, the drawings showing containers 41 from which the colour is fed through pipes 48 to the squeegees 8. Means may also be provided for regulating the rate of flow or the pressure under which the colour is delivered to the squeegees 8 and the pressure of the latter on the patterns 10 may also be adjustable if desired.

Having now particularly described and ascertained the nature of our said invention and in what manner the same is to be performed, we declare that what we claim is:

1. In a screen printing machine for textiles the combination, comprising, a main frame, an endless belt supported for movement on the frame and having holes adjacent its longitudinal edges, reciprocable ratchet rack means periodically engageable in the belt holes and while engaged therein moving the belt through a predetermined distance, channel means supporting the ratchet rack means for relative movement and periodically moving same to engagement in the belt holes, motor means supported by the main frame, means driven by the motor and reciprocating the ratchet rack means, means reciprocating the channel means and driven by the motor, and means operable adjacent the end of one stroke of the channel means and moving the same and the ratchet rack means to cause the latter to engage the belt holes.

2. In a screen printing machine for textiles, the combination according to claim 1, wherein, the means reciprocating the ratchet rack means is unidirectionally driven by the motor.

3. In a screen printing machine for textiles, the combination according to claim 1, wherein, the means reciprocating the channel means comprises lever means connecting the main frame and channel means, and cam means driven by the motor and oscillating the lever means.

4. In a screen printing machine for textiles, the combination according to claim 1, wherein, the means operable adjacent the end of one stroke of the channel means are cam means thereon and cooperating with the main frame.

5. In a screen printing machine for textiles,

the combination according to claim 1, also comprising, pattern carrying subframe means movable to and from engagement with the belt, means operable adjacent the end of one stroke of the channel means and moving the subframe means from engagement with the belt simultaneously with the engagement of the belt by the means moving same.

6. In a screen printing machine for textiles, the combination according to claim 5, wherein, the subframe moving means are cam means carried by the channel means.

7. In a screen printing machine for textiles, the combination according to claim 5, also comprising, squeegee means cooperating with the pattern and reciprocable lengthwise thereof and of the belt.

8. In a screen printing machine for textiles, the combination according to claim 7, also comprising, means driven by the motor and reciprocating the squeegee means.

9. In a screen printing machine for textiles, the combination according to claim 8, wherein, the means reciprocating the squeegee includes a half gear driven by the motor and a crank intermittently driven by the half gear.

10. In a screen printing machine for textiles, the combination, comprising, a main frame, an endless belt supported for movement on the frame and having holes adjacent its longitudinal edges, reciprocable ratchet rack means periodically engageable with the belt holes and while engaged therein moving the belt through a predetermined distance, means reciprocating the rack means and including a crank arm and a vertical shaft fixed to the arm, subframes movable onto and from the belt, squeegees movable backwards and forwards and stationary when the subframes are raised; means moving the squeegees, said means including, a main driving shaft geared to the vertical shaft and a half gear driven by the main shaft, cams carried by the main shaft, levers pivoted to the frame and intermittently rocked by the cams, channel means supporting the rack means and carrying inclined projections, rollers carried by the frame and engaged by the projections and raising the channel means and racks to engage the teeth thereof with the belt holes, and a motor driving the main shaft.

11. The combination according to claim 10, wherein the racks carry inclined projections, and further comprising rollers carried by the subframes and engaged by the projections on the racks to lift the subframes from the belt at the same time as the channel means and racks are raised.
